UNITED STATES PATENT OFFICE.

ELMER C. MOORE, OF BALTIMORE, MARYLAND, ASSIGNOR TO J. E. HANGER, INC., A CORPORATION OF THE DISTRICT OF COLUMBIA.

ARTIFICIAL LIMB.

1,108,462.

Specification of Letters Patent. Patented Aug. 25, 1914.

Application filed May 7, 1914. Serial No. 836,904.

To all whom it may concern:

Be it known that I, ELMER C. MOORE, a citizen of the United States, residing at Baltimore, in the State of Maryland, have invented new and useful Improvements in Artificial Limbs, of which the following is a specification.

My invention relates to artificial legs, and pertains more particularly to the harness for 10 operating the lower leg section forwardly on the knee joint, and lifting same in stepping.

The object of my invention is to produce a harness to be operated by the shoulders of the wearer attached to the lower-leg portion 15 of an artificial leg below the knee joint for lifting and moving forward the lower leg in walking.

Another object thereof is to produce means in said harness to obtain a variable 20 direct tug by the shoulder suspenders to move the leg forward on the knee joint, and to retain the position of the suspenders and overcome the tendency thereof to "crawl" when roller connections are provided for the 25 suspenders and operating strips.

A further object of my invention is to provide means for slightly binding the knee joint when the weight of the body is shifted to the opposite leg in walking, and a still 30 further object thereof is to produce a more simple, cheap and efficient artificial leg suspender than has heretofore been attained.

To these ends, my invention includes the 35 combination and arrangement of component parts to be hereinafter described and more particularly pointed out in the claims.

In the accompanying drawings, in which like characters indicate similar parts, Figure 1 is a front elevation of my invention; Fig. 40 2 is a side view thereof; Fig. 3 is a rear view of the same; Fig. 4 is a detail view of my rocking pivoted bar, and Fig. 5 is a sectional view of the same.

Referring now to the drawings, 1 indicates the thigh section of an artificial limb 45 having a stump socket 2 therein, and 3 designates the lower-leg section, suitably pivoted on the thigh section at 4 to form a knee joint.

On each side of the lower-leg section, I 50 attach the flexible strips 5 and 5', said strips being secured at their lower ends to the lower leg section at 5''. The upper ends thereof extend above the knee joint, and are 55 free and unattached, and have secured there-

on the rigid metal plates 6. Pivottally mounted on said plates, I provide the cross-bars 7. Said cross-bars are pivoted intermediate their ends on the pins 8, and are provided adjacent each of its outer ends 60 with buttons 9 on which the shoulder straps 10 may be attached. I also provide on each side of my artificial leg, an elastic strip 11 and 11' attached at their lower ends at the rear of the lower-leg section at approximately the "calf" portion, and attached at their upper ends to the side strips 5 and 5'. Said elastic strip is normally slightly 65 shorter than the distance between its upper and lower attachments when the side strips 70 5 and 5' are drawn taut by the tension of the shoulder straps, by which elastic tension the knee is slightly bent on its pivot and the lower section slightly raised before moving the leg forward in the act of stepping. 75

The shoulder straps 10 to which the side strips 5 and 5' are attached may be adjusted by the buckles 13 to be comfortably worn over the shoulders of the wearer, and it will be appreciated that the position of the 80 shoulder straps will not change in the acts of walking, by reason of their fixed attachment on the side strips, and it will be further apparent that the rocking bar 7 pivottally mounted thereon, will permit a comfortable latitude of motion without releasing a direct control of the lower limb 85 through the non-elastic flexible side strips.

As shown in the drawings, a ring A may 90 be inserted in each of the side strips below the knee joint, and when desired said rings may be tied with a connecting thong B.

Having thus described my invention, what I claim as new, and desire to be secured by Letters Patent, is— 95

1. In an artificial leg, the combination with a thigh section and a lower-leg section pivottally jointed thereto, of a flexible strip attached at its lower end to the lower-leg section on each side thereof, a rocking cross bar pivoted on the upper free end of each of said flexible strips, intermediate their ends, and shoulder straps attached to the ends of said rocking bar, substantially as described. 100

2. In an artificial leg, the combination with a thigh section and a lower-leg section pivottally jointed thereto, of a flexible strip attached at its lower end to the lower-leg section on each side thereof, shoulder straps 110

2
attached to the free ends of said side strips, and elastic strips attached to said side strips adjacent the free ends, and attached at their opposite ends to the rear of the lower-leg section, substantially as described.

3. In an artificial leg, the combination with a thigh section and a lower-leg section pivotally jointed thereto, of a flexible strip on each side thereof attached at their lower ends to the opposite sides of the lower-leg section, a rigid plate secured on the upper free ends of said strips, a rocking cross bar pivoted on each of said plates, buttons on the outer ends of said cross bar, and shoulder straps attached to said buttons, substantially as described.

4. In an artificial leg, the combination with a thigh section and a lower-leg section

pivotal jointed thereto, of a flexible strip on each side thereof attached at their lower ends to the opposite sides of the lower-leg section, a rocking cross bar pivoted on the upper ends of said side strips, flexible strips attached at their upper ends to said side strips adjacent their upper ends and attached at their opposite ends to the rear of the lower-leg section, and shoulder straps attached to the outer ends of said rocking bars, all adapted to swing said lower-leg section forward on the joint, substantially as described.

ELMER C. MOORE.
